CLAIM

The ornamental design for a multi-functional wireless charger, as shown and described.

DESCRIPTION

FIG. 1 is a first perspective view of a multi-functional wireless charger showing our new design;
FIG. 2 is second perspective view thereof;
FIG. 3 is third perspective view thereof;
FIG. 4 is a front view thereof;
FIG. 5 is a rear view thereof;
FIG. 6 is a left side view thereof;
FIG. 7 is a right side view thereof;
FIG. 8 is a top plan view thereof; and,
FIG. 9 is a bottom plan view thereof.

The broken lines depict portions of the multi-functional wireless charger and form no part of the claimed design.
